UNITED STATES PATENT OFFICE.

EDMOND W. T. RICHMOND, OF ROMFORD, ENGLAND.

DESIGN FOR A GAS-STOVE.

SPECIFICATION forming part of Design No. 33,877, dated January 8, 1901.

Application filed December 11, 1900. Serial No. 39,557. Term of patent 7 years.

To all whom it may concern:

Be it known that I, EDMOND WALTER TYRRELL RICHMOND, a subject of the Queen of Great Britain, residing in Summercourt, Romford, in the county of Essex, England, have invented and produced a new and original Design for Gas-Stoves, of which the following is a specification.

The accompanying drawing shows a perspective view of a gas-stove embodying my design.

The leading features of my design are the annular body portion A, the radial wings B, extending upwardly from the body portion and inwardly into the space contained within the body portion, the laterally-projecting han-

dle C, and the plate D below the body portion and separated therefrom by the feet E, to which it is secured.

The body portion is ornamented by a Grecian border, as is also the handle portion. The top of the body portion is further ornamented by a series of holes a.

I claim—

The design for a gas-stove, substantially as herein shown and described.

In testimony whereof I have hereunto subscribed my name.

EDMOND W. T. RICHMOND.
